(57) **CLAIM**

The ornamental design for a cardboard container as shown and described.

DESCRIPTION

FIG. 1 is a top perspective view of the cardboard container; FIG. 2 is a bottom perspective view thereof;

FIG. 3 is a front view thereof;

FIG. 4 is a rear view thereof;

FIG. 5 is a first side view thereof;

FIG. 6 is a second side view thereof;

FIG. 7 is a top view thereof;

FIG. 8 is a bottom view thereof;

FIG. 9 is a top perspective view thereof, showing the cardboard container with a lid removed;

FIG. 10 is a top view thereof, showing the cardboard container with the lid removed; and,

FIG. 11 is an exploded view thereof, showing the cardboard container including the lid.

The broken lines in the drawings depict portions of the cardboard container that form no part of the claimed design. The cardboard container varies in length within the double sinusoidal lines as illustrated in FIGS. 1-11.

In FIGS. 1-6, 9 and 11; the cardboard container is shown with a symbolic break in its length. The appearance of any portion of the article between the break lines forms no part of the claimed design.
